David Evins, New York, N. Y., assignor to Johnston & Murphy, Newark, N. J., a corporation of New Jersey
Application May 18, 1955, Serial No. 36,078

Term of patent 7 years

(Cl. D7—7)

FIG. 1.

FIG. 2.

Fig. 1 is a view in top plan of a shoe showing my new design.

Fig. 2 is a view in side elevation of a side of the shoe, the design being the same on both sides thereof.

The dominant features of the design reside in the portions thereof shown in full lines in the accompanying drawings.

I claim:

The ornamental design for a shoe, as shown and described.
